Martin Aakervik, Los Angeles, Calif., assignor to Modeline Company of California Inc., Los Angeles,
Calif., a corporation of California

Application June 10, 1959, Serial No. 56,306

Term of patent 14 years

(Cl. D48—20)

Fig. 1 is an elevational view of a lamp showing my new design;

Fig. 2 is a top plan view thereof; and

Fig. 3 is an elevational view taken from the right of Fig. 1, the opposite side not shown being substantially the same.

The dominant features of my design reside in the portions shown in full lines.

I claim:

The ornamental design for a lamp, as shown and described.
